UNITED STATES PATENT OFFICE.

HENRY LAERTIGUE, OF PARIS, FRANCE, ASSIGNOR TO THE SOCIÉTÉ GÉNÉRALE DES TÉLÉPHONÉS, OF SAME PLACE.

TELEPHONE-EXCHANGE AND APPARATUS THEREFOR.

SPECIFICATION forming part of Letters Patent No. 267,905, dated November 21, 1882.

Application filed December 31, 1881. (No model.) Patented in France July 30, 1881, No. 144,184; in Belgium August 31, 1881, No. 55,607; in England September 1, 1881, No. 3,809; in Italy November 14, 1881; in Austria December 11, 1881, No. 33,252, and in Spain January 28, 1882.

To all whom it may concern:

Be it known that I, HENRY LAERTIGUE, a citizen of the French Republic, residing in Paris, France, have invented certain new and 5 useful Improvements in Telephonic-Exchange Offices and in Commutators and other Appliances Appertaining Thereto, of which the following is a specification.

The object of this invention is to systematize 10 and simplify the accessories and operations at central telephonic offices, where are assembled the wires of the numerous subscribers' circuits.

Instead of extending a single wire from the 15 central office to the subscriber's telephone and then grounding it, I employ a double or returning wire, thus rendering the circuit entirely metallic, and I bind the two insulated wires together in a cotton wrapping, and seven 20 (more or less) of these wrapped double wires are grouped together into a cable and covered with lead. Each such cable will serve seven subscribers. A great number of such cables are laid, in the street-sewers by preference, 25 when practicable, or in pipes or conveyers beneath or above the ground.

In the accompanying drawings, Figure 1 is a vertical section of the ground and building where the central office is located, showing 30 the complete connections from the street-sewer to the commutator-tables, where the connections are made; and Fig. 2 is a plan of the office appurtenances, partly in horizontal section. The remaining figures are detail views, 35 which will be best understood after a general description of Figs. 1 and 2 has been given.

The lead-covered cables, (lettered *a a*), after emerging from the sewer, enter the building where the central office is located, at A, Fig. 40 1, through an aperture in the wall. This aperture is covered with a perforated plate, C. (Shown on a larger scale in vertical transverse section in Fig. 3, and in elevation in Fig. 4.) Each cable *a* passes through one of the perforations *b* in this plate, whereby the cables are kept distinct. The holes *b b* are only large 45 enough to admit the cables, whereby the entrance of sewer-gases and foul emanations into the building is prevented.

I make no claim in this application to the 50 portion of my invention thus far described, reserving such claim for the subject of a future application.

After passing the plate C, the cables *a a* are or may be separated into two groups, D D, 55 one of which passes along the ceiling, and the other of which descends through a box or way, B, to the floor, and both extend to a connecting-frame, E. This frame (shown in section in Fig. 2) consists of panels joined together in box form and strengthened by corner-posts *c c*. The two side panels have each a large circular opening, E', around which are a number of sectors, F F, Fig. 1, one to each cable *a*. One of these sectors is shown separately and enlarged in Fig. 5, which is a front elevation. The groups D D, on arriving at the frame E, separate, and the cables *a a* diverge or radiate, one passing to each sector F, the cables of the ceiling-group extending to those 60 sectors above the center of the frame E, and those of the floor-group joining the sectors 70 below the center.

Near each sector F is an eye, *d*, and each cable *a* passes through the one of these eyes 75 nearest its sector, is then denuded of its leaden sheath, and its seven double wires *e e* are spread apart and passed through seven holes, *f f*, Fig. 5, formed through the panel of the frame E. Each double wire *e*, as it emerges 80 through its hole *f*, is denuded of the wrapping by which the two insulated wires are bound together, and the latter pass under a clamping-plate, *h*, on the sector F, which plate bears the name and address of the subscriber supplied 85 by the wires. From thence the two wires are separated and their naked ends are clamped by binding-screws *i i* on an ebonite plate, *j*. The screws *i i* are respectively connected through two copper strips with two binding-screws, *i' i'*, on the opposite end of the plate *j*. To the screws *i' i'* are connected the separated end of a pair of wires, *k*, inclosed in a sheathing of paraffine, which "paraffine strand," as I shall call it, has attached to it a plate, *l*, bearing the subscriber's number, and thence is carried to the margin of the opening E', where it passes between two rubber knobs, *n*, Fig. 5,

and thence is carried, with all the other strands, through the passage or channel G to the commutator-racks or operator's desks H H, (seen in Figs. 1 and 2,) which I have shown as being located on the floor above.

5 In Fig. 2 I have shown, for simplicity's sake, a connection-frame, E, of two faces or panels; but it may be made of one, three, or more.

The commutator-racks H H are shown in Fig. 2 as arranged in two rows and set back to back, the strands k k passing between the rows and spreading to their different racks. Fig. 6 is a vertical transverse section of the racks. Each rack H has fixed to it the commutators and indicators for a certain number of subscribers—say, for instance, twenty-five—and hence it is preferable to group the strands k k as they leave the frame E into cables of twenty-five strands in each, and to conduct each such cable to one of the racks, where the strands are separated and the two wires of each strand are joined to their own commutator. On each rack H the twenty-five indicators are placed above at I, the twenty-five commutators are placed at J, and below these are arranged, at K, a series of conjunctors that serve to establish electrical communication from one rack to another, as shown best in the front elevation, Fig. 11.

30 The commutators I employ are of the kind known as "American jack-knives," which I have modified to adapt them to the use of two wires, instead of a single wire grounded. I superpose two jack-knives, arranging one directly in front of the other. Fig. 7 is a horizontal longitudinal mid-section through the double jack-knife, cut in the plane of the lines 7 7 in Fig. 8. Fig. 8 includes two vertical longitudinal sections cut in the planes of the two lines 8 8 in Fig. 7, the upper view being a section through the rear and the lower view a section through the front jack-knife. Fig. 9 is an elevation of the double peg used with the commutator, and Fig. 10 is a longitudinal mid-section thereof.

45 Referring to Figs. 7 and 8, M is the metallic plate or body portion of the front jack-knife, and M' is that of the rear jack-knife. Both are fastened by bolts O and O' to the rack H, these bolts being insulated from the metallic plates M M', and the latter being insulated from each other by an ebonite sheathing, N. A metallic plug, w, penetrates the plate M', being insulated from it by the sheathing N. 50 A screw, q, re-establishes connection between the plate M and the bolt O, and a screw, q', likewise connects the plate M' with the plug w. Two holes or sockets, t and t', are formed through the front plate, M, and back of these 55 are formed a socket, u, in the plug w, and a socket, u', in the back plate, M'. The sockets u and u' are smaller than the holes t t', and serve as continuations thereof. Beneath the front plate is the usual spring, m, having a contact-point, p, which normally touches a branch from the bolt O and a plunger, o, projecting

transversely into the socket t. The back plate, M', is provided with a like spring, m', inversely arranged, having a point, p', connecting with the bolt O', and a plunger, o', projecting into the socket u'. The ends of the two wires in the paraffine strand k are connected, one to the plate M, the other to the plate M', Fig. 8, and the wires x and y, leading to the relay R, which works the annunciator, are connected respectively to the bolts O and O'. The relay need not be used, in which case R will designate the annunciator.

55 The peg or plug P (shown in Figs. 9 and 10) is connected with a cord of two wires, and consists of a handle with a split ferrule, r, at its end, and a split rod or pin, s, projecting beyond the ferrule and insulated therefrom. The ferrule r is joined to one wire of the cord, the pin s to the other. The ferrule is of such size as to fit in the sockets t or t', the pin of such size as to fit into u or u'. With this commutator the annunciator (or relay) R can be put either in derivation or in the main circuit with the telephone. In the first case, in the position of waiting, a current from the subscriber's battery passes through M, the screw q, the bolt O, the wire x, the annunciator R, the wire y, the bolt O', the point p', the spring m', and the plate M', and the annunciator operates and notifies the attendant. The latter then inserts into the socket t u the peg P of his telephone, whereupon his telephone is in one branch of the circuit extending through the flexible cords, as shown by the dotted lines T 90 in Fig. 7, while the annunciator is in a separate branch following the path just described. The attendant may then communicate with the subscriber; or, if the peg P be put into the socket t' u', communication is also established with the subscriber; but in this case the circuit to the annunciator is broken at p', and the current can only pass through the peg P and its wires to the attendant's telephone and back. Thus to establish communication between two subscribers a cord is employed with a double peg P at each end, and one peg is thrust into the right-hand socket of one commutator, while the other is put into the left-hand socket of the other commutator, 100 whereby the annunciator of only one subscriber is left in derivation for the purpose of receiving the signal denoting that the conversation is finished, the connection with the other annunciator being broken. To put the 105 annunciator R in the same circuit with the telephone, instead of in derivation, the screws q q' are withdrawn (or lifted) and a wire, v, (shown by a dotted line,) is employed. The current then does not divide when the attendant inserts the peg of his telephone in the left-hand socket, but flows first through his telephone and then through the annunciator. 110

Fig. 11 shows the commutator-racks H H in front elevation on a larger scale than Fig. 1. 115 As before mentioned, the commutators are grouped in clusters of twenty-five on each rack

or desk, it being desirable to include in the same group those subscribers who most frequently communicate with each other. I have here shown two groups of twenty-five commutators in each rack, two panels composing a rack. The conjunctors K K are to enable communication to be made between the commutators of subscribers who are on different racks. These conjunctors consist of a series of double plates (shown in detail in Fig. 12) having a socket into which the peg P will fit, and arranged in vertical and horizontal rows, as shown in Fig. 11. The vertical rows of each rack are numbered 1 2 3 4 5 6. Each conjuncto-
10 plates are electrically connected with the plate on the same horizontal line of each like-numbered row. It is understood that the conjuncto-plate of row 1 are for the use of sub-
15 scribers on the first rack, those in row 2 for the second rack, and so on. Suppose that sub-
20 scriber No. 15 of the first section or panel of the second rack wishes to communicate with subscriber No. 87 of the second section of the third rack. The attendant, after having com-
25 municated with the subscriber, will thrust one peg P into commutator No. 15 and the peg at the other end of the cord into some conjuncto-
30 in the row 2, and he will then in like manner connect the corresponding conjuncto-
35 of row 2 of the third rack with commutator No. 87, after having called subscriber No. 87.

The lower rows of conjunctors may serve to establish communication, either permanent or transitory, from one central office to another or others.

I claim as my invention—

1. The combination of connection-frame E, consisting of an annular panel having a series of radial conducting-connections fixed to its face adjacent to its central opening, with an equal series of wires entering from its back through said opening, and the end of each confined to one of said connections, and with another series of wires carried around its surface outside of said series of connections, and each wire extending inward to and terminating at one of said connections, whereby each wire of the inner series is joined through one of said connections with the corresponding wire of the outer series, substantially as set forth.

2. The connection-frame E, consisting of a board or panel having an opening, E', lined with a series of sectors, F F, and provided with a corresponding number of eyes, d d, and each sector having a greater number of perforations or eyes, e e, and a number of binding-connections corresponding to the number of

eyes e e, combined and arranged substantially as set forth.

3. The combination, with double wires leading to the subscriber's telephone, of a double-jack-knife commutator, consisting of two superposed interinsulated jack-knives, the plate of each being connected with one of said wires, 65 combined and arranged substantially as set forth.

4. A commutator consisting of the combination of two jack-knife commutators insulated from each other, arranged one against the other, 70 with their ends reversed, and with communicating sockets, substantially as set forth.

5. A commutator consisting of the combination of two plates, M M', and two bolts, O O', all insulated from each other, springs m and 75 m', making contact with bolts O O', plungers o o', and sockets t t' and u u', substantially as set forth.

6. The combination, with a commutator consisting of two superposed interinsulated jack-knives having communicating sockets, of a peg, P, consisting of a ferrule, r, and pin s, insulated from each other and adapted to fit said sockets, and a flexible cord of two insulated wires, one wire connected to said ferrule, 85 the other to said pin, substantially as set forth.

7. The combination, to form a commutator, of two plates, M M', insulated from each other, sockets t t' through the front plate, M, a plug, w, entering the back plate, M', back of the 90 socket t, and insulated from said plate, a socket, u, in said plug, forming a continuation of the socket t, a socket, u', in the plate M', forming a continuation of the socket t', springs m m', and plungers o o', substantially as set forth. 95

8. The combination and arrangement of the racks H H with the commutators J J, and conjunctors K K on each rack, said conjunctors consisting each of two plates insulated from each other, and each plate of each conjuncto- 100 on one rack being electrically connected with the corresponding plate of the corresponding conjuncto- on each other rack, substantially as set forth.

9. The conjunctors K K, consisting of double superposed interinsulated plates having communicating sockets, the like plates of corresponding conjunctors being electrically connected, substantially as set forth.

In witness whereof I have hereunto signed my name in the presence of two subscribing witnesses.

HENRY LARTIGUE.
